UNITED STATES PATENT OFFICE.

DAVID WOLFE BRUCE, OF NEW YORK, N. Y.

DESIGN FOR FONT OF PRINTING-TYPES.

Specification forming part of Design No. 7,993, dated January 12, 1875; application filed December 8, 1874.
[Term of Patent 14 years.]

To all whom it may concern:

Be it known that I, DAVID WOLFE BRUCE, of the city, county, and State of New York, have originated and designed a new Pattern for Printing-Types, which I describe as follows:

The nature of my design is clearly shown in the accompanying typographic impression, to which reference is made, and which differs from every other kind of type in style and proportion. It consists of Roman capitals, figures, and points skeletoned, with latitudinal

lines run in the face, which has a diagonal black shade on the right side and other portions, to aid the perspective, and a diagonal-ray shade attached to said black shade.

What I claim as my invention, and desire to secure by Letters Patent, is—

The design or pattern for a font of printing-types, herein shown and described.

DAVID WOLFE BRUCE.

Witnesses:

H. M. HALL,
V. B. MUNSON.
